United States Patent Office

Des. 228,831
Patented Oct. 30, 1973

228,831

NURSE'S CAP

Clifford Wayne Shumate, Carlisle, Ky., assignor to Johnson & Johnson

Filed Aug. 18, 1971, Ser. No. 172,960

Term of patent 14 years

Int. Cl. D2—03

U.S. Cl. D2—255

FIG. 1.

FIG. 2.

FIG. 3.

FIG. 1 is a top perspective view of a nurse's cap showing my new design;

FIG. 2 is a bottom perspective view thereof; and

FIG. 3 is a side elevational view of the cap in an opened position.

I claim:

The ornamental design for a nurse's cap, substantially as shown.
